(57) **CLAIM**

The ornamental design for a camera, as shown and
described.

DESCRIPTION

FIG. 1 is a top, front and right side perspective view of a
camera;

FIG. 2 is a front elevation view thereof;

FIG. 3 is a right elevation view thereof;

FIG. 4 is a left elevation view thereof;

FIG. 5 is a top plan view thereof; and,

FIG. 6 is a bottom plan view thereof.

The broken lines depict portions of the camera in which the
design is embodied that form no part of the claimed design.
Additionally, the dash-dot lines denote the boundary of the
claim and form no part of the claimed design.

1 Claim, 5 Drawing Sheets
